UNITED STATES PATENT OFFICE.

HAROLD J. MATTHEWS, OF VANCOUVER, CANADA.

STEAM-GENERATING BOILER.

Application filed August 23, 1924. Serial No. 733,817.

This invention relates to a steam generating boiler of the vertical, multitubular class which has been specially designed for use with logging engines, but is applicable to any hauling or winding engine where the boiler is seated between the side frames of the engine and the width between these frames is to a large extent standardized.

Where a cylindrical boiler is applied to such an engine its diameter is necessarily limited to the space between the frames, and that limitation frequently prevents an adequate boiler being furnished to meet the present day requirements of such engines.

Where a cylindrical boiler so limited is insufficient for the engine requirements, attempt has been made to overcome the restriction by lengthwise enlarging the fire-box between the frames. Although this elongation of the fire-box affords an increased grate area, an enlarged combustion chamber and a corresponding slight increase of the heating surface, so long as the boiler above the fire-box remains cylindrical, the full advantage of this enlargement of the fire-box is not utilized, because the available tube area and water and steam space is still subject to the cylindrical restriction, and further, owing to the offset at the junction of the elongated fire-box to the cylindrical boiler shell, a serious obstruction is offered at the junction offset to the passage of steam generated in the water space surrounding the fire-box to the steam space of the cylindrical shell.

In the boiler, which is the subject of this application, the shell, throughout its entire height, is elongated in its cross section to fully utilize the space available between the engine side frames. The fire-box being correspondingly enlarged, its crown plate and the upper end plate of the boiler shell which constitutes the tube plates of the boiler, provide accommodation for an increased number of tubes, whereby an increased steam generating surface and a greater water space are rendered available.

The walls of the fire-box are suitably stayed to the correspondingly shaped outer shell, and the flattened portions of the boiler shell above the fire-box are directly stayed to one another by plate stays that will not restrict the water space or interfere with the circulation, but afford a straight line flow throughout.

A boiler so designed may be used in the restricted space available and be efficiently

and practically stayed that the flat sides of the shell may have a pressure efficiency not less than that of the longitudinal seams of the boiler, whereby the allowable working pressure will be the same on all parts of the boiler shell.

The invention is particularly described in the following specification, reference being made to the drawings by which it is accompanied, in which:

Fig. 1 is a sectional plan inverted on the line 1—1 in Fig. 2, and

Fig. 2 is a vertical section on the line 2—2 in Fig. 1.

In these drawings 2, 3 represent the boiler shell, 2 being the semi-cylindrical portions, the diameter of which or shorter axis of the cross section corresponds approximately to the distance between the side frames of the engine, and 3 are the flat portions connecting the portions 2 and lengthwise enlarging the cross section area of the boiler shell.

This cross section area of the boiler shell is uniform throughout the entire height of the boiler from the lower edge 4 adjacent the grate to the upper tube plate 5. Within the lower part of this shell 2, 3 is a similarly shaped fire-box 6 preserving a water space 7 between it and the shell 2, 3. The tubes 8 extend between the lower tube plate 9 which forms the crown of the fire-box 6 and the upper tube plate 5 which forms the head of the boiler shell 2, 3.

The wall 6 of the fire-box is stayed to the outer shell 2, 3 by the customary stays 10 screwed or otherwise secured and pitched the required distance apart to stand the pressure imposed on the boiler. Above the fire-box the flat areas 3 of the shell are tied together 95 by plate stays 11 which are spaced between the tubes and are secured to the shell between angle irons 12 riveted thereto.

In the upper end of the boiler immediately below the upper tube plate 5, a dry pipe 100 15 is secured across between the flat sides 3, which pipe is bent upwards as close as practicable to the upper tube plate and is perforated along the upper side; whereby dry steam may be drawn from the boiler to either 105 one or both sides as desired.

A boiler of this class is thus provided which is adapted to a laterally restricted dimension and has withal a heating surface and a water space which are considerably in 110 excess of what is obtainable in existing practice, which requires the shell of a boiler to

be cylindrical, at least above the fire-box, irrespective of the fact that the flattened portions of the shell can be effectively stayed to the strength of all other parts of the 5 boiler.

The fact that this boiler affords, in addition to its greater heating surface of both fire-box and tubes, a straight line circulation between the water space of the fire-box 10 and that surrounding the tubes, and also allows a more uniform draught through the tubes, are in themselves most desirable attainments.

Although in the drawings the tubes 8 are 15 spaced apart where the plate stays 10 between the flattened sides 3 of the boiler shell pass, it must be understood that the tubes may be spaced the standard minimum distance apart and yet allow sufficient room 20 for the stays.

Having now particularly described my invention, I hereby declare that what I claim as new and desire to be protected in by Letters Patent, is:

25 1. A vertical multitubular boiler, comprising a shell which is laterally flattened in cross section throughout the entire height of the boiler, a fire-box within the lower part

of the shell with a water space between it and the shell, means for staying the flattened 30 sides of the shell to the fire-box, plate stays extending across between the flattened sides of the shell above the fire-box, said plate stays being of a height to extend from adjacent the top of the boiler to adjacent the 35 top of the fire-box and tubes extending between the crown of the fire-box and the upper end plate of the shell.

2. A vertical multitubular boiler, comprising a shell which is laterally flattened in 40 cross section throughout the entire height of the boiler, a correspondingly shaped fire-box secured within the lower part of the shell to maintain a water space between it and the shell, stays connecting the flattened sides of 45 the shell to those of the fire-box and above the fire-box plate stays connecting the flattened sides of the shell together, said plate stays being of a height to extend from adjacent the top of the boiler to adjacent the 50 top of the fire-box and tubes between the crown of the fire-box and the upper end plate of the shell.

In testimony whereof I affix my signature.

HAROLD J. MATTHEWS.
